UNITED STATES PATENT OFFICE.

MATTHEW D. COADY, OF AUBURN, RHODE ISLAND, ASSIGNOR TO JAMES N. HENRY,
OF PROVIDENCE, RHODE ISLAND.

CURTAIN-ROD BRACKET.

1,400,726.

Specification of Letters Patent. Patented Dec. 20, 1921.

Application filed August 5, 1921. Serial No. 429,939.

To all whom it may concern:

Be it known that I, MATTHEW D. COADY, a citizen of the United States, residing at Auburn, in the county of Providence and 5 State of Rhode Island, have invented certain new and useful Improvements in Curtain-Rod Brackets, of which the following is a specification.

My invention relates to a bracket adapted 10 to support curtain rods and has for its essential objects the avoidance of defacement of the window casing by the bracket attaching means; facility of insertion and security of such attaching means; the avoidance of 15 the necessity of a bracket attaching plate or screws; the formation of the entire structure and attaching means from a single blank of sheet metal; and to insure a secure engagement of the bracket and curtain rod. 20 To the above ends essentially my invention consists in such parts and in such combinations of parts as fall within the scope of the appended claims.

In the accompanying drawings which 25 form a part of this specification,

Figure 1 is a plan elevation of my bracket showing the adjacent end of an engaged curtain rod and a portion of the window casing in section,

Fig. 2, a section on line 2—2 of Fig. 1,

Fig. 3, a side elevation of the bracket disengaged from the rod,

Fig. 4, a longitudinal section of the same, and

Fig. 5, a perspective view of the same.

Like reference characters indicate like parts throughout the views.

In detail my bracket is cut and shaped by suitable tools from a flat strip of thin resili- 40 ent metal to form an outer end housing portion 7 integral with which are longitudinally disposed substantially parallel semi tubular wings 8 outwardly tapering from the dome, and whose edges 10 are slightly spaced from

each other. Integral with the flaring ends 45 of the wings are substantially parallel smooth unbent shanks 12 provided with pointed ends 13. In the present instance these shanks are located diametrically opposite each other at the longitudinal edges 10 50 of the wings. The wings are resilient and therefore somewhat compressible.

The described bracket is attached to the window casing 15 by driving the pointed members 12 into the woodwork. The end of 55 the curtain rod 17 may be manually pushed over the bracket as shown in Figs. 1 and 2, thereby compressing the resilient portions of the wings to bring one of the edges 10 of each wing into contact with the adjacent 60 edge of the other wing, thus insuring a snug fit of the bracket and rod.

I claim:

1. In a bracket for curtain rods, an end portion, wings integral therewith, and 65 smooth attaching shanks integral with the free ends of the wings and extended beyond the same and provided with points.

2. In a bracket for curtain rods, an end housing portion, semi-tubular wings integral therewith to snugly engage the inner wall of a tubular rod, and attaching shanks 70 upon the ends of the wings.

3. In a bracket for curtain rods, an end housing portion, and flaring substantially 75 parallel wings integral with the housing portion to snugly engage the inner wall of a tubular rod.

4. In a bracket for curtain rods, an end housing portion, semi-tubular resilient wings 80 integral with the housing portion to snugly engage the inner wall of a tubular rod, and attaching members upon the ends of the wings extended beyond the wings.

In testimony whereof I have affixed my 85 signature.

MATTHEW D. COADY.
